BOILER DROP PLUG

Robert N. Miller, Rosemont, Pa., assignor to The Pennsylvania Railroad Company, Philadelphia, Pa., a corporation of Pennsylvania

Application June 6, 1940, Serial No. 339,079

1 Claim. (Cl. 122—504.3)

This invention relates to safety plugs for steam boilers and, more particularly, to the type comprising a tubular body-member with a drop-plug normally sustained therein by a fusible bushing adapted, under a given temperature, to melt and release the drop-plug, whereby escaping steam will effect an audible warning that the water in the boiler has lowered to an undesirable level.

The primary object of this invention is to provide an improved drop-plug of the indicated species including novel features whereby the efficiency is greatly enhanced.

Another object is provision of a drop-plug of the type above referred to that is devoid of any "creeping" or "sticking" tendencies, which is simple to manufacture, easy to install, cheap in production, and withal is positive and reliable in action.

Other objects and ancillary advantages of this invention will appear as the nature thereof is better understood, said invention consisting substantially in the novel features of construction, combinations and arrangements of parts herein fully described and illustrated by the accompanying drawing; wherein similar reference characters are used to designate corresponding parts throughout the several views; and then finally pointed out and specifically defined in the concluding claim.

In the drawing:

Fig. 1 is a vertical section through one typical form of drop-plug constructed in accordance with this invention, and preferably adapted for application in locomotive boiler crown sheets, a fragmentary portion whereof is shown.

Fig. 2 is an underside plan view of the same.

Fig. 3 is a perspective view of a fusible-bushing included in the drop-plug structure.

Fig. 4 is a perspective view of the releasable component or drop-plug detached from the associated body-member.

Fig. 5 is a section similar to Fig. 1 of a slightly modified form of the invention.

Fig. 6 is an underside plan view of the preceding figure.

Fig. 7 is a central vertical section through a further typical form of the invention; and,

Fig. 8 is an underside plan view of the said figure.

In the following detailed disclosure of the embodiments of this invention shown by the accompanying sheet of drawings, specific terms will be employed for the sake of clarity, but it is to be understood that such terms are used in a descriptive sense and not for purposes of limitation.

Each specific term is intended to include all technical equivalents which serve in a similar manner to accomplish an analogous purpose.

In the practice of this invention, and referring descriptively to the embodiment thereof, shown more particularly by Figs. 1-4, inclusive, the body-member of the drop-plug is comprehensively designated by the numeral 1, said member consisting preferably of a machined annular body portion including a taper-bored upper part 2 and an externally taper-threaded lower part 3, for screw engagement in a correspondingly-threaded aperture 5, provided for its reception in the crown-sheet 6.

15 Internally, the body-shell portion 3 is appropriately formed to define a polygonal-shaped socket 7 for insertion of a suitable key whereby the said member is threaded into or drawn-out of the crown-sheet aperture 5; and said socket 20 has an adjoining annular groove 8, for preventing formation of "burr" during finishing of the socket, with a relatively smaller counterbore 9 communicating with the lower end of the plug main bore 10. This bore 10, it is to be particularly noted, is preferably outwardly divergent in form, substantially approximating to a three-quarter inch taper in a longitudinal dimension of one-foot; and it is conveniently press-fitted with a complementally-tapered fusible-bushing 11.

25 30 Into this bushing 11 is press fitted the releasable closure or drop-plug 12, said plug having a taper conforming with that of the bore 10, the major or upper end 13 having a diameter slightly less than the smaller diameter of said bore. "Creeping" of the plug 12 in service is thus eliminated by compression of the fusible-bushing 11, incidental to the press-fit application of said plug; while "sticking" is effectively prevented when the plug 12 is released for blowing out. In addition, 35 the drop-plug 12 may be provided in its smaller end 14 with an axial recess 15 for purposes of proper centering of said plug, relative to the bore 10, when such plug is initially secured in position either by a pressure operation, or otherwise.

40 45 Incidentally, it is here remarked that the externally screw-threaded portion 3 is of a taper substantially approximating that of the bore 10 and plug 12, but reversely inclined to positively ensure an absolutely liquid-proof joint within 50 the crown-sheet 6. The fusible-bushing 11 may be produced by casting, extrusion, or expanding of a suitable alloy tubing, cut to the desired lengths, and preferably composed of fifteen per cent tin with eighty-five per cent lead; while 55 there is no sweat solder bond between the shell

1 and the bushing 11, or between said bushing and the drop-plug 12.

In the modification of Figs. 5 and 6, the only difference over the preceding description resides in the fact that the socket portion 16 of the plug 1 is, in this instance, square with the diagonally-opposing angular corners filleted at 17; accordingly similar reference characters are applied, to obviate unnecessary repetitive explanation.

Referring now to Figs. 7 and 8, it will be observed that the screwthreaded portion 3, of the cast shell 1, is formed with a plain annular extension 18 of less diameter, said extension having diametrically opposed notches 19 for application thereto of a conventional spanner-wrench, or other manipulator, whereby the shell 1 can be easily engaged in or removed from the crown-sheet 6. In addition thereto, the drop-plug 12 is lengthened to project well below the tapering bore 10, into the cylindrical hollow 20 of the shell 1, so as to provide an extension 21 in the firebox area to serve as a means for accelerating heat conduction to the fusible-bushing 11. In this form of the invention, an annulus 22 of the bushing fusible composition may be extruded or otherwise applied around the plug extension 21, as indicated in broken line section, at the base of the bore 10.

From the foregoing it will be readily apparent that in the event of low water in the boiler, or over the crown sheet 6, which results in uncovering the top portion 13 of the drop-plug 12, the fusible bushing 11, that normally is mechanically held to the shell 1 and said plug, becomes overheated sufficiently to melt and releases the drop-plug 12, whereupon the latter is blown out by steam pressure in the boiler into the firebox, it being obvious that the tapering formation of said plug effectively prevents "creeping" or "sticking;" as well as greatly facilitating its release when the fusible-bushing commences to melt.

Having thus described my invention, I claim:

A drop plug for attachment in the crown sheets of boiler furnaces comprising an annular component having a uniformly and downwardly tapered bore, a conformatory bushing of fusible material and even thickness fitted in said bore, and a frusto-conical plug of complementary taper engaged in the bore of the fusible bushing, said plug having its larger end of slightly less area than that of the smaller end of the aforesaid annular component bore.

ROBERT N. MILLER.
